STUDY CARRELL

John L. Gianfagna, Marietta, Ohio, and Vytautas K. Beleckis and Stephen F. McKeon, Parkersburg, W. Va., assignors to Sperry Rand Corporation, New York, N.Y., a corporation of Delaware

Filed Mar. 12, 1969, Ser. No. 16,210

Term of patent 14 years

Int. Cl. D6—01

U.S. Cl. D33—11

FIG. 1.

FIG. 3.

FIG. 2.

FIG. 4.

FIG. 5.

FIG. 7.

FIG. 6.

FIG. 8.

FIG. 1 is a perspective of a study carrell showing our new design;

FIG. 2 is a front view thereof;

FIG. 3 is a side elevational view thereof;

FIG. 4 is a rear view thereof;

FIG. 5 is a perspective view of another embodiment of the study carrell shown in FIG. 1;

FIG. 6 is a front view of the FIG. 5 embodiment;

FIG. 7 is a side view of the FIG. 5 embodiment; and

FIG. 8 is a rear view of the FIG. 5 embodiment.

The sides not shown in FIGS. 3 and 7 are mirror images of the sides shown.

We claim:

The ornamental design for a study carrell, substantially as shown and described.
